EGG BEATER

Filed April 12, 1928

Inventor

T. M. Nippert.

By *Lacey, Lacey,* Attorneys

UNITED STATES PATENT OFFICE.

TESSIE M. NIPPERT, OF STURGEON BAY, WISCONSIN.

EGG BEATER.

Application filed April 12, 1928. Serial No. 269,556.

The present invention is directed to improvements in egg beaters.

The primary object of the invention is to provide an egg beater of the woven wire type so constructed that the wire strands are secured to the frame in such manner as to prevent wear incident thereto when coming in contact with the sides of a bowl during the beating operation.

10 It has been heretofore the practice to mount the wire fabric within the frame by wrapping the strands around the frame, consequently placing the same in such position as to come in contact with the sides 15 of the bowl, resulting in wear, and consequent breakage of the strands, and it is to overcome this defect that the present invention has been perfected.

While the drawing illustrates a preferred 20 embodiment of the invention, it is to be understood that in adapting the means to meet specific needs and requirements the design may be varied and such other changes in the minor details of construction may be 25 resorted to within the scope of the invention as claimed, without departing from the spirit thereof.

For a full understanding of the invention and the merits thereof, reference is to be 30 had to the following description and the drawing hereto attached, in which,

Figure 1 is a plan view of the device.

Figure 2 is a fragmentary detail perspective view.

35 Corresponding and like parts are referred to in the following description and designated in the several views of the drawing by like reference characters.

The numeral 1 designates the frame which 40 is formed from a single piece of suitable metal bent into oval shape, the body 2 thereof being rectangular in cross section and relatively thin, said body being provided with a plurality of perforations 3 in which 45 are secured certain of the strands 4 of the woven wire fabric 5.

The terminals 6 of the body 2 are left round and are twisted together to provide a shank 7, the outer terminals of the strands 50 8 of the shank being reversely bent to provide side rods 9 which have their inner

ends secured to the terminals 6 of the body 2, as at 10, thus maintaining the rods in spaced relation upon opposite sides of the shank 7. It will be thus seen that the shank 55 7 and rods 9 constitute a handle 11 which is not only rigid, but offers a comfortable grip for the user. Since the strands 8 are twisted the body of the frame will be held rigid, and owing to the fact that the strands 60 4 are secured inwardly of the outer edge of the body 2 of the frame, the same will not come in contact with the sides of a bowl, consequently preventing wear of the strands and resultant breakage.

65 From the foregoing description it will be seen that a beater has been provided and is constructed in such manner that the strands thereof will be effectively protected against wear, thus prolonging the life of the device.

70 The device is primarily designed for beating eggs, but can be made of stouter material in order that it can be used as a cake mixer.

75 Having thus described the invention, I claim:

1. A beater consisting of a wire having the intermediate portion flattened and formed in its length with a plurality of perforations, and bent to provide a frame, and having the end portions brought together and intertwined to form a handle, and a wire filling across the frame and engaging the perforations thereof leaving the outer 80 marginal portion of the frame smooth and free from projecting parts.

2. A beater consisting of a wire having the intermediate portion flattened and perforated throughout its length, and bent to provide a frame of oval form, and having the end portions brought together and intertwined for a distance to form a shank and rebent to provide side rods and looped about the frame adjacent the shank, and a wire 85 filling across the frame and engaging the perforations thereof leaving the outer marginal portion of the frame smooth and free from projecting parts.

90 In testimony whereof I affix my signature.

TESSIE M. NIPPERT. [L. s.]
